US00D929628S

(12) **United States Design Patent** (10) **Patent No.:** **US D929,628 S**
(45) **Date of Patent:** **** Aug. 31, 2021**

(54) **FLASHLIGHT WITH AN ELECTRONIC INSECT REPELLENT**

(71) Applicant: **West Coast Imports, Inc.**, Commerce, CA (US)

(72) Inventor: **Vinay Saboo**, Commerce, CA (US)

(73) Assignee: **WEST COAST IMPORTS, INC.**, Commerce, CA (US)

(**) Term: **15 Years**

(21) Appl. No.: **29/694,652**

(22) Filed: **Jun. 12, 2019**

(51) LOC (13) Cl. **26-02**

(52) U.S. Cl.

USPC **D26/38**

(58) **Field of Classification Search**

USPC D26/37-44, 46-52; D10/111-115

CPC ... F21Y 2115/10; F21Y 2113/13; F21L 4/027;

F21L 4/025; F21L 4/085; F21V 23/0414;

(57) **CLAIM**

The ornamental design for a flashlight with an electronic insect repellent, as shown and described.

DESCRIPTION

FIG. 1 is a perspective view of a flashlight with an electronic insect repellent.

FIG. 2 is a front view thereof;

FIG. 3 is a first side view thereof;

FIG. 4 is a rear view thereof;

FIG. 5 is a second side view thereof;

FIG. 6 is a bottom view thereof; and,

FIG. 7 is a top view thereof.

(Continued)

The broken lines shown in the figures are environmental and form no part of the claimed design.

1 Claim, 4 Drawing Sheets
